UNITED STATES PATENT OFFICE.

GEORGE THOMAS JOSEPH, OF COVINGTON, VIRGINIA.

RAIL-JOINT.

No. 802,991.

Specification of Letters Patent.

Patented Oct. 31, 1905.

Application filed February 18, 1905. Serial No. 246,223.

To all whom it may concern:

Be it known that I, GEORGE THOMAS JOSEPH, a citizen of the United States, and a resident of Covington, in the county of Alleghany and State of Virginia, have invented a new and useful Improvement in Rail-Joints, of which the following is a specification.

My invention is an improvement in rail-joints; and it consists in certain novel constructions and combinations of parts, as will be hereinafter described and claimed.

In the drawings, Figure 1 is a perspective view of a joint embodying my invention. Fig. 2 is a longitudinal section thereof. Fig. 3 is a cross-section on about line 3 3 of Fig. 2. Fig. 4 is a detail perspective view of the connecting-bar. Fig. 5 is a detail bottom plan view of one of the rail ends, and Fig. 6 is a detail inverted perspective view of one of the rail ends.

The meeting ends of the rails A A may be alike, and these rails may be alike at their opposite ends, so they may be turned end for end whenever desired, especially when a rail has been worn on one side and it is desired to reverse it in order to bring the other side into wearing position.

In connecting the meeting ends of the rails I employ a connecting-bar B, having a base B' and an upright web B². The base B' is in the form of a double dovetail and may be of extreme width at the ends b' of the base and taper thence gradually to a point b² midway between the ends of the connecting-bar. This connecting-bar is also symmetrical and alike at both ends, so it may be turned end for end whenever desired. The base B' of the connecting-bar operates to connect the meeting ends of the rails, and the web B², extending upwardly into the web of the rails, tends to steady the connecting-bar of the base and also provides the portion which is exposed to view by the lateral openings in the ends of the rails, as will be presently described.

The rails A are formed with the base-plates A', the webs A², and the treads A³. The base A' of the rails is notched at a' at its ends, so that the coinciding notches a' may receive a spike C (see Fig. 1 of drawings) in order to limit the creeping movement of the rails as desired. In its base each rail is provided at its ends with a tapered recess D gradually widening from the end d of the rail toward the inner or opposite end d' of the recess. This recess D is fitted to receive one of the dovetail sections of the connect-

ing-bar B, and an upright groove or recess E extends upwardly above the recess D and communicates therewith, as will be understood from Figs. 3, 5, and 6 of the drawings, 60 a squared shoulder d² forming the top wall of the recess D throughout the major portion of length of said recess on opposite sides of the groove E, as best shown in Figs. 3, 5, and 6 of the drawings. The groove E extends 65 upwardly within the web A² of the rail and receives the web B² of the connecting-bar, as shown in Fig. 3.

The rails A are provided in the ends of their webs A² with slots or openings a², which 70 communicate with the groove E in the web of the rail and expose to view the middle portion of the web B² of the connecting-bar B when the parts are applied as shown in Fig. 1. This is important, as it enables the track- 75 walker to determine by a glance whether the connecting-bar is fractured or the integrity of the connection has not been disturbed.

In practice I make the tapered recesses D somewhat larger than the dovetail-sections 80 B' of the base of the connecting-bar, so that a limited longitudinal movement of the rails is permitted for expansion and contraction in use.

It will be understood from Figs. 4, 5, and 6 85 that the recesses and upright grooves in the bases and webs of the rails conform to the connecting-bar B and that the upright grooves E are of a width approximately equal to that of the small ends of the tapered recesses D and that the web B is of a thickness 90 approximately equal to the width of the dovetail base portions B' at the smaller end of the latter where they unite about midway between the ends of the connecting-bar, as best 95 shown in Fig. 4 of the drawings.

The upright web B² is important, as it braces and steadies the dovetail base portions B' in place and tends to prevent any twisting thereof in the use of the invention.

It may be desired in practice to arrange the joint of the rails over a tie, as shown in Fig. 2; but it will be understood that this is not necessary, as ordinarily the connecting-bar is of sufficient length to bridge the space between any two ties and will form a firm support for the ends of the rails in all positions of the parts.

The construction is simple, easily applied, and forms a secure connection between the 110 meeting ends of the rails.

Having thus described my invention, what I

claim as new, and desire to secure by Letters Patent, is—

1. The combination substantially as herein described of the rails provided in the ends of their base-plates at their outer edges with notches for a spike and having in the under sides of their bases tapered recesses which extend from and gradually widen from the ends of the rails, the upright grooves formed in the webs of the rails and extending longitudinally above and communicating at their lower ends with the tapered recesses in the rails, slots being formed in the ends of the rails and communicating with the said upright recesses and a connecting-bar having a double dovetail, or tapered base portion fitting the tapered recesses in the base of the rails and also provided with an upright longitudinally-extending web which fits within the grooves of the rail and is exposed to view through the lateral openings formed in the webs of the rails, all substantially as and for the purpose set forth.

2. The combination of the rails provided in their ends with the tapered recesses formed in the under sides of the base of the rails, and gradually widening as they depart from the ends of the rail and also having upright grooves communicating at their lower ends with the said tapered recesses and approximately equal to the width of the said recesses at their narrow ends and the connecting-bar having a double dovetail base fitting in the tapered recesses of the rails and an upright

web fitting in the grooves of the rails, substantially as set forth.

3. The combination of the rails provided in their ends with base-recesses gradually tapering from the ends of the rails and with upright grooves communicating at their lower ends with said recesses, the connecting-bar having dovetail base portions fitting in said tapered recesses, and an upright web fitting in the upright grooves of the rails, substantially as set forth.

4. The combination of the connecting-bar having the dovetail base portions and the upright web, and the rail ends provided in the under sides of their base portions with recesses and grooves to receive the said connecting-bar, substantially as set forth.

5. The combination of the rails provided with the tapered recesses in the under faces of their base portions, and with upright grooves communicating with said recesses, and the connecting-bar having base portions and an upright web fitted to the said rail ends, substantially as set forth.

6. In a rail-joint a connecting-bar having a double tapered dovetail base increasing in width from a middle point toward its ends and an upright web thereon, substantially as set forth.

GEORGE THOMAS JOSEPH.
